UNITED STATES PATENT OFFICE

MATTHEW J. GREEN, OF PORTSMOUTH, VIRGINIA

INDIVIDUAL ASH RECEPTACLE

Application filed September 24, 1931. Serial No. 564,922.

This invention relates to an ash receptacle primarily adapted for manufacture in a compact size to be carried in the pocketbook, in the pocket of clothing, on a watch chain or otherwise although capable of manufacture and use in larger sizes if desired.

It is particularly aimed to provide a novel construction which will provide an individual ash receptacle.

10 It is further aimed to provide a novel construction which when open, affords a ledge or support for the cigarette, and a construction which may be effectively closed while in the pocketbook, pocket or the like and which may 15 be readily emptied.

Various additional objects and advantages will become apparent from a consideration of the description following taken in connection with accompanying drawings illustrating 20 an operative embodiment.

In said drawing:—

Figure 1 is a view of the device in side elevation,

25 Figure 2 is a front elevation thereof,

Figure 3 is a plan view,

Figure 4 is a central vertical sectional view taken on the line 4—4 of Figure 3,

Figure 5 is a vertical sectional view taken on the line 5—5 of Figure 4,

30 Figure 6 is a horizontal sectional view taken on the line 6—6 of Figure 2, and

Figure 7 is a detail sectional view taken on the line 7—7 of Figure 4.

Referring specifically to the drawing, the 35 device comprises a body or receptacle 10 which may be of any desired shape except where necessary to carry out the invention. The receptacle 10 is open at the bottom but normally closed by a closure member 11 having a flange 12 frictionally and removably telescoped therein.

Below the top, one portion of the receptacle is provided with a cigarette supporting 45 wall 13 which may have an arcuate supporting member 14 fastened thereto. The remainder of the receptacle extends above the support 13 forming a hood 15, which is open above and at the side adjacent the support 13. To close such open space 16, a slidable plate 17 is provided, whose movement is guid-

ed by flanges 18 and by a transverse rod or pin 19 secured to the body 10. Lowering movement of the plate 17 is limited by an enlargement 20 thereon with the top of the receptacle while upward movement is limited through the abutment of a flange 21 on the plate with the rod 19. In its uppermost position, an opening 22 through the plate, is exposed in line with the support 14 and hence the cigarette disposed on the latter and extending through the opening 22 may be manipulated to shake the ashes therefrom so as to fall within the receptacle. The receptacle may be closed at any desired time by operating the plate 17. Attention is called to the fact that there is sufficient frictional engagement between the flanges 18 and plate 17, and adjacent parts, to hold the plate in any position to which it is adjusted. In order to anchor the device to a watch chain or the like when desired, an eyelet 23 is provided on the body.

Various changes may be resorted to provided they fall within the spirit and scope of the invention.

I claim as my invention:—

1. An ash receptacle of the class described having a cigarette-supporting portion, a closure plate for the receptacle, said closure plate being movable to expose an opening whereby access to the interior of the receptacle may be had to drop ashes, a rod extending across the casing, a flange on the plate adapted to abut the rod to limit opening movement, and said plate having the opening therethrough.

2. A device of the class described comprising a receptacle, a hood thereon, a plate closing one side of the hood and provided with an opening, said plate being movable whereby the opening will be exposed or concealed, a cigarette-supporting portion on the receptacle adapted for support of a cigarette in line with the opening when exposed.

3. A device of the class described comprising a receptacle, a hood thereon, a plate closing one side of the hood and provided with an opening, said plate being movable whereby the opening will be exposed or concealed,

a cigarette-supporting portion on the receptacle adapted for support of a cigarette in line with the opening when exposed, a flange on said plate, and a rod in the receptacle engageable by the flange to limit the movement of the plate.

In testimony whereof I affix my signature.
MATTHEW J. GREEN.
